US0D1028777S

(12) **United States Design Patent** (10) **Patent No.:** **US D1,028,777 S**
(45) **Date of Patent:** **** May 28, 2024**

(54) **JEWELRY ARTICLE**

(71) Applicant: **PARAMOUNT JEWELS, LLC**, New York, NY (US)

(72) Inventor: **Sumay Bhansali**, Scarsdale, NY (US)

(73) Assignee: **PARAMOUNT JEWELS, LLC**, New York, NY (US)

(**) Term: **15 Years**

(21) Appl. No.: **29/897,322**

(22) Filed: **Jul. 13, 2023**

(51) **LOC (14) Cl.** **11-01**

(52) **U.S. Cl.**

USPC **D11/38**; D11/26

(58) **Field of Classification Search**

USPC D11/1-16, 26-29, 37, 38, 39

CPC A44C 5/0084; A44C 5/0092; A44C 5/12;

A44C 7/00; A44C 9/00

See application file for complete search history.

(57) **CLAIM**

The ornamental design for a jewelry article, as shown and described.

DESCRIPTION

FIG. 1 is a front and top perspective view of a jewelry article showing my new design.

FIG. 2 is a top plan view thereof.

FIG. 3 is a bottom plan view thereof.

FIG. 4 is a front elevation view thereof.

FIG. 5 is a rear elevation view thereof.

FIG. 6 is a left side elevation view thereof; and,

FIG. 7 is a right side elevation view thereof.

The broken lines in the drawings represent portions of the jewelry article that form no part of the claimed design. The dash-dot-dash lines in the drawings represent a claim boundary and form no part of the claimed design.

1 Claim, 5 Drawing Sheets
